ROOF GUTTER ASSEMBLY

Hervey N. Andrews, San Francisco, Calif.

Application February 18, 1946, Serial No. 648,436

14 Claims. (Cl. 108—28)

1

This invention relates in general to, and it is an object to provide, an improved roof gutter or eaves trough assembly for buildings.

Another object of the invention is to provide a roof gutter assembly which includes an initially separate gutter and continuous supporting unit; the supporting unit being applied when the building is being roofed, but the gutter remaining until the last for attachment, by novel means, to the supporting unit whereby to assure against damage to the gutter by ladders, etc. during building operations.

Another object of the invention is to provide a roof gutter assembly, as in the preceding paragraph, in which the continuous supporting unit is mounted on the roof adjacent the edge and includes an upstanding continuous lip over which is engaged a matching continuous hook formed along the upper and inner edge of the gutter; the supporting unit also including a flange projecting outwardly from the fascia of the building for engagement and connection with the gutter in stabilizing relation thereto.

A further object of the invention is to provide a roof gutter assembly, as described, wherein the continuous supporting unit for the gutter includes a novel gravel guard and roofing stop formed therein.

A further object of the invention is to provide a practical and effective device suitable for the purposes for which it is designed.

These objects are accomplished by means of such structure and relative arrangement of parts as will fully appear by a perusal of the following specification and claims.

In the drawings:

Fig. 1 is a sectional perspective view of the invention as in use.

Fig. 2 is a similar view but illustrates a modification.

Referring now more particularly to the characters of reference in the drawings, and at present to Fig. 1, the initially separate supporting unit for the eaves trough or roof gutter comprises a longitudinal strip of sheet metal formed to include a vertical skirt 1 and a rearwardly and upwardly inclined flange 2; the skirt 1 being adapted to be secured against the fascia 3 of a building by nails 4, while the flange 2 is adapted to rest on the roof on top of the dry sheet 5, as applied on top of the roof sheathing 6. The flange 2 is held in place by nails 7, and is disposed adjacent but short of the edge of the roof. Between said flange and the vertical skirt 1 the longitudinal

2

strip of sheet metal is formed with an upwardly opening channel 8.

Along the upper edge of the channel 8 the metal of the longitudinal strip is folded so as to form an upstanding, roofing and gravel stop 9, which stop is of inverted V-shape in cross section. The composition roof 10 is applied over the dry sheet 5 and abuts the stop 9, as shown; the gravel 11 being applied to such composition roof 10 in the usual manner.

Along the lower edge of the channel 9 the metal of the longitudinal strip is folded so as to form a continuous upstanding lip 12 which is disposed at a rearward incline; said lip extending along the outer edge of the roof and substantially directly above the vertical skirt 1.

The roof gutter or eaves trough is indicated at 13, and in the present embodiment includes a vertical back wall 14 and a horizontal bottom 15. Along its outer and upper edge the gutter is formed with a protective roll 16, and transverse stays 17 connect at intervals between the roll 16 and the upper rear edge of the gutter.

Along said upper rear edge the gutter is formed with a continuous hook 18 which opens downwardly, and which hook is adapted to matchingly engage over the upstanding lip 12 which defines the lower edge of the channel 8; said continuous hook 18 being of a length such that it extends into the channel 8 to a termination closely adjacent the bottom of the latter.

The vertical skirt 1 is formed, along the lower edge thereof, with a continuous, seat-forming flange 19 which projects horizontally outwardly for supporting engagement with the bottom 15 of the gutter 13.

When a building is under construction the described supporting unit for the gutter is applied with the roof, but the initially separate gutter 40 remains unattached, so as to prevent damage to the latter, as would otherwise occur by ladders being placed thereagainst, etc. When the roof is in place and the building construction substantially complete the gutter 13 is affixed by first 45 engaging the continuous hook 18 over the lip 12, with the vertical back wall 14 flush against the vertical skirt 1; the continuous, seat-forming flange 19 then engaging beneath the horizontal bottom 15 in supporting relation to the latter.

In order to prevent displacement of the gutter 13, there is provided a number of longitudinally spaced clips 20 secured on the bottom 15 of said trough, and said clips, which extends transversely of the gutter, include upstanding fingers 21 at their inner ends, which fingers engage between

the lower edge portion of the vertical skirt 1 and the facia 3. The dry sheet 5 terminates short of said lower edge portion of the vertical skirt 1 whereby to permit of access of said fingers 21 between the skirt 1 and facia 3, as described.

After the gutter is engaged on the supporting unit by placement of the continuous hook 18 over the lip 12, the channel 8 is filled with a mastic material 22, whereby water from the composition roof 10 sheds across the channel 8, over the continuous hook 18, and into the gutter 13.

In the embodiment of Fig. 2, the roof gutter assembly includes the same combination as described in connection with Fig. 1, but here the gutter 23 is of semi-circular configuration in cross section, as shown. To provide adequate support for this type of gutter, the front skirt 24 of the supporting unit is concave to matchingly engage the gutter 23 from its upper rear edge downwardly a substantial distance. Thence the front skirt 24 is flanged inwardly, as at 25, with said flange including a foot 26 which abuts against the facia 27. The foot 26 is secured to the facia 27 by means of nails 28.

The front skirt 24, together with the flange 25 and foot 26, is of course continuous or full-length.

This type of gutter is applied in the same manner as described in connection with Fig. 1, but here the longitudinally spaced clips 29 include no upturned fingers, and are formed to matchingly engage the flange 25; said clips 29 being secured to said flange 25 by means of screws 30.

The described invention, in either of its embodiments, provides, in combination, a very practical and effective roof gutter assembly, and roofing and gravel stop; the structure being easy to attach and readily assembled.

While wood construction is shown, the invention is applicable to concrete or other types of construction, with suitable fasteners for attaching thereto.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A roof gutter assembly comprising a longitudinal strip adapted to be secured on a roof along its edge, said strip including an upwardly projecting longitudinal lip disposed closely adjacent said edge, a roof gutter, and a longitudinal hook formed on the upper rear edge of the gutter adapted to engage over the lip in gutter-supporting relation.

2. A roof gutter assembly comprising a longitudinal strip adapted to be secured on a roof along its edge, said strip including an upwardly projecting longitudinal lip disposed closely adjacent said edge, a roof gutter, and a longitudinal hook formed on the upper rear edge of the gutter adapted to engage over the lip in gutter-supporting relation; said strip including an upwardly projecting, longitudinal, roofing and gravel stop disposed in rearwardly spaced relation to said lip.

3. A roof gutter assembly comprising a longitudinal strip adapted to be secured on a roof along its edge, said strip including an upwardly projecting longitudinal lip disposed closely adjacent said edge, a roof gutter, and a longitudinal hook formed on the upper rear edge of the gutter adapted to engage over the lip in gutter-supporting relation; said strip including an upwardly projecting, longitudinal, roofing and gravel stop disposed in rearwardly spaced relation to said lip, whereby to form a channel therebetween, and a mastic material filling said channel.

4. A roof gutter assembly as in claim 1 in which the lip is inclined rearwardly and upwardly, and the longitudinal hook matchingly engaging said lip.

5. A roof gutter assembly as in claim 3 in which the lip and stop are both formed by folds in said strip intermediate the side edges thereof.

20 6. A roof gutter assembly comprising an initially separate, longitudinal strip adapted to be secured on a roof along its edge, said strip including a skirt depending from its front edge and an upwardly projecting, longitudinal lip disposed closely adjacent said front edge, an initially separate roof gutter, a longitudinal hook formed on the upper rear edge of the gutter adapted to engage over the lip in gutter-supporting relation, and means projecting forwardly from the depending skirt in gutter engaging and supporting relation.

35 7. A roof gutter assembly comprising an initially separate, longitudinal strip adapted to be secured on a roof along its edge, said strip including a skirt depending from its front edge and an upwardly projecting, longitudinal lip disposed closely adjacent said front edge, an initially separate roof gutter, a longitudinal hook formed on the upper rear edge of the gutter adapted to engage over the lip in gutter-supporting relation, and means projecting forwardly from the depending skirt in gutter engaging and supporting relation; the gutter having a flat bottom, and said means including a horizontal flange projecting forwardly from the lower edge of the depending skirt.

40 8. A roof gutter assembly comprising an initially separate longitudinal strip adapted to be secured on a roof along its edge, said strip including a skirt depending from its front edge and an upwardly projecting, longitudinal lip disposed closely adjacent said front edge, an initially separate roof gutter, a longitudinal hook formed on the upper rear edge of the gutter adapted to engage over the lip in gutter-supporting relation, and means projecting forwardly from the depending skirt in gutter engaging and supporting relation; the gutter having a flat bottom, said means including a horizontal flange projecting forwardly from the lower edge of the depending skirt, and spaced elements securing the gutter and skirt against separation in a horizontal direction.

45 9. A roof gutter assembly comprising an initially separate longitudinal strip adapted to be secured on a roof along its edge, said strip including a skirt depending from its front edge and an upwardly projecting, longitudinal lip disposed closely adjacent said front edge, an initially separate roof gutter, a longitudinal hook formed on the upper rear edge of the gutter adapted to engage over the lip in gutter-supporting relation, the gutter being rounded in cross section and said skirt including a portion symmetrically engaging the under side of said gutter, and means securing the gutter and skirt against separation.

10. A roof gutter assembly comprising an initially separate longitudinal strip adapted to be secured on a roof along its edge, said strip including a skirt depending from its front edge and an upwardly projecting, longitudinal lip disposed closely adjacent said front edge, an initially separate roof gutter, a longitudinal hook formed on the upper rear edge of the gutter adapted to engage over the lip in gutter-supporting relation, the gutter being rounded in cross section and said skirt including a portion symmetrically engaging the under side of said gutter, and means securing the gutter and skirt against separation; the skirt including a rearwardly extending flange below said gutter engaging portion, and spaced elements on the gutter overlying and secured to said flange.

11. A roof gutter assembly comprising an initially separate strip adapted to be secured on a roof along its edge, said strip having a channel formed therein closely adjacent said edge, an initially separate roof gutter, and a longitudinal hook on the upper rear edge of the gutter adapted to engage in said channel in gutter supporting relation.

12. A roof gutter assembly comprising an initially separate strip adapted to be secured on a roof along its edge, said strip having a channel formed therein closely adjacent said edge, an initially separate roof gutter, and a longitudinal

30

hook on the upper rear edge of the gutter adapted to engage in said channel in gutter supporting relation; there being a mastic material filling said channel after engagement of the hook therein.

5. 13. A roof gutter assembly comprising an initially separate strip adapted to be secured on a roof along its edge, said strip having a channel formed therein closely adjacent said edge, said channel being defined on the lower side by an upstanding, longitudinal lip and defined on the upper side by an upstanding, longitudinal, roofing and gravel stop, an initially separate gutter, and a longitudinal hook on the upper rear edge of the gutter adapted to engage over the lip in gutter supporting relation.

10. 14. A roof gutter assembly comprising an initially separate strip adapted to be secured on a roof along its edge, said strip having a channel formed therein closely adjacent said edge, said channel being defined on the lower side by an upstanding, longitudinal lip and defined on the upper side by an upstanding, longitudinal, roofing and gravel stop, an initially separate gutter, and a longitudinal hook on the upper rear edge of the gutter adapted to engage over the lip in gutter supporting relation; the lip inclining upwardly and rearwardly, the hook matchingly engaging the same, and a mastic material filling the channel after engagement of the hook on the lip.

HERVEY N. ANDREWS.
